UNITED STATES PATENT OFFICE

154,780

DESIGN FOR A SHOE SOLE PRESS

Myron Jaffe, Cleveland Heights, Ohio

Application November 4, 1947, Serial No. 142,304

Term of patent 14 years

(Cl. D63—1)

To all whom it may concern:

Be it known that I, Myron Jaffe, a citizen of the United States, residing in the city of Cleveland Heights, county of Cuyahoga, and State of Ohio, have invented a new, original, and ornamental Design for a Shoe Sole Press, of which the following is a specification, reference being had to the accompanying drawing, forming a part thereof.

Figure 1 is a perspective view of the shoe sole press, embodying my new design;

Figure 2 is a right side view thereof;

Figure 3 is a front view thereof;

Figure 4 is a top view thereof; and

Figure 5 is a rear view thereof.

I claim:

The ornamental design for a shoe sole press, substantially as shown.

MYRON JAFFE.
